UNITED STATES PATENT OFFICE.

FREDERICK G. GRUEN, OF CINCINNATI, OHIO.

DESIGN FOR A WRIST-WATCH CASE.

53,655.

Specification for Design.

Patented July 29, 1919.

Application filed March 19, 1919. Serial No. 283,676. Term of patent 7 years.

To all whom it may concern:

Be it known that I, FREDERICK G. GRUEN, a citizen of the United States of America, and a resident of Cincinnati, in the county of Hamilton and State of Ohio, have invented a new, original, and ornamental Design for a Wrist-Watch Case, of which the following is a specification.

The figure is a plan view of a wrist watch case, showing my new design.

Copies of this patent may be obtained for five cents each, by addressing the "Commissioner of Patents, Washington, D. C."

I claim—

The original design for a wrist watch case as shown.

In testimony whereof, I have hereunto subscribed my name this 24 day of February, 1919.

FREDERICK G. GRUEN.
